US0D1066242S

(12) **United States Design Patent** (10) **Patent No.:** **US D1,066,242 S**
(45) **Date of Patent:** **** Mar. 11, 2025**

(54) **CHARGING STATION**

(71) Applicant: **Volta Charging, LLC**, San Francisco, CA (US)

(72) Inventors: **Scott A. Mercer**, Pacifica, CA (US); **Alex Prodaniuk**, Pacifica, CA (US); **Kayla Matheus**, San Francisco, CA (US); **Christian Julio Santander**, Bad Riechenhall (DE); **Julian Schloemer**, Salzburg (AT); **Marco Wilhelm**, Salzburg (AT)

(73) Assignee: **VOLTA CHARGING, LLC**, San Francisco, CA (US)

(**) Term: **15 Years**

(21) Appl. No.: **29/913,856**

(22) Filed: **Oct. 10, 2023**

Related U.S. Application Data

(63) Continuation of application No. 29/866,777, filed on Sep. 27, 2022, now Pat. No. Des. 1,005,938, which is a continuation of application No. 29/710,632, filed on Oct. 24, 2019, now Pat. No. Des. 967,012.

(57) **CLAIM**

The ornamental design for a charging station as shown and described.

DESCRIPTION

FIG. 1 is a front perspective view of the charging station showing our new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines immediately adjacent the shaded areas represent the bounds of the claimed design while all other broken lines depict portions of the charging station that form no part of the claimed design; the broken lines form no part of the claimed design.

1 Claim, 6 Drawing Sheets
